COMBINATION CLOSURE CAP AND DISPENSER

Sidney M. Libit, Glencoe, Ill.

Application May 14, 1957, Serial No. 46,165

Term of patent 14 years

(Cl. D58—26)

Fig. 1.

Fig. 2.

Fig. 3.

Fig. 1 is a front elevational view of a combination closure cap and dispenser showing my new design;

Fig. 2 is a side elevational view thereof, the view from the opposite side being the same; and

Fig. 3 is a top plan view thereof.

I claim:

The ornamental design for a combination closure cap and dispenser, substantially as shown and described.
